(57) **CLAIM**

The ornamental design for a pedal boat, as shown and described.

DESCRIPTION

1. Pedal boat

The present design relates to a pedal boat.

1.1 is a top, front, left side perspective view of a pedal boat embodying my new design;

1.2 is a right side perspective view thereof;

1.3 is a left side perspective view thereof;

1.4 is a front perspective view thereof;

1.5 is a top rear perspective view thereof;

1.6 is a top front perspective view thereof; and

1.7 is a bottom perspective view thereof.

The broken showing of dark areas visible at the sides of the pedal boat do not form part of the claimed design, and the broken line showing of a ladder at the bow, as well as a rope at the stern, do not form part of the claimed design.
